Primary Examiner — Joseph Kukella*Assistant Examiner* — Arva P Adams**(57) CLAIM**

The ornamental design for a bottle lid, as shown and described.

DESCRIPTION

FIG. 1 is a top perspective view of a bottle lid, showing my new design;

FIG. 2 is a bottom perspective view of FIG. 1;

FIG. 3 is a front view of FIG. 1;

FIG. 4 is a rear view of FIG. 1;

FIG. 5 is a left view of FIG. 1;

FIG. 6 is a right view of FIG. 1;

FIG. 7 is a top view of FIG. 1; and,

FIG. 8 is a bottom view of FIG. 1.

Any shading and cross-hatching are not surface ornamentation but are utilized to illustrate the surface contours of the bottle lid in the drawings.

The broken lines show portions of the bottle lid that form no part of the claimed design.
